Primary Examiner — Michael C Stout

Assistant Examiner — Katelin G Kloberg

(57) **CLAIM**

The ornamental design for bed as shown and described.

DESCRIPTION

FIG. 1 is a front, left, and top perspective view of a bed, showing my new design;

FIG. 2 is a rear, left, and bottom perspective view thereof;

FIG. 3 is a front, right, and top perspective view thereof;

FIG. 4 is a front elevational view thereof;

FIG. 5 is a rear elevational view thereof;

FIG. 6 is a left elevational view thereof;

FIG. 7 is a right elevational view thereof;

FIG. 8 is a top plan view thereof;

FIG. 9 is a bottom plan view thereof; and,

FIG. 10 is a front, left, and top perspective view thereof when a drawer of the bed is opened.

The broken lines in the drawings depict portions of the bed that form no part of the claimed design.

1 Claim, 10 Drawing Sheets
